LEWIS LARSEN, OF MENOMINEE, MICHIGAN, ASSIGNOR TO HEYWOOD-WAKEFIELD COMPANY, OF BOSTON, MASSACHUSETTS, A CORPORATION OF MASSACHUSETTS

FURNITURE FRAMING AND METHOD OF MAKING THE SAME

Application filed June 17, 1929. Serial No. 371,338.

This invention relates to improvements in furniture framing and method of making the same and it consists of the matters hereinafter described and more particularly 5 pointed out in the appended claim.

In some branches of the furniture industry, bent wood is employed in the production of chairs, stools, tables and the like. The wood thus employed is usually cylindrical in cross sections and is referred to as "dowel stock". In this branch of the industry the exterior surface of the stock is substantially plain and smooth. The reed furniture industry absorbs large amounts of 10 such stock as framing material and usually such stock is circumferentially beaded to simulate rattan, or reed wrapping on those portions of the frames exposed to view in a finished article of reed or like furniture.

20 However, in both instances the stock is treated as with hot water to make it pliable and bendable to form. Sometimes such water treated stock splits or cracks in the bending thereof and again such stock even after 25 it has been incorporated in a piece of furniture and has dried out, splits and splinters, which of course is objectionable.

The primary object of the invention is to 30 provide a material suitable for bending into desired shapes for furniture framing, which is indeed much stronger than all wood framing and will not split, crack or splinter while the same is being bent into shape or after it 35 has been incorporated into an article of furniture.

Still another object of the invention is to 40 provide a framing for such purpose, made of a thin light weight metallic tubing and reinforced upon the inside so that the same may be bent without splitting or cracking, the tubing stock being so thin as to easily permit the driving of nails, brads or tacks thereinto in the manner of driving the same into wood.

45 These objects of the invention as well as others together with the many advantages thereof, will more fully appear as I proceed with my specification.

In the drawings:-

50 Fig. 1 is a view in side elevation of a piece

of thin walled, sheet metal tubing employed in carrying out one form of my invention before the same has been operated upon in accordance with other steps of the invention as will later appear.

55 Fig. 2 is a view in side elevation of said tubing after it has been operated upon to provide a circumferentially beaded surface thereon to simulate a rattan or reed wrapped appearance after finishing. Fig. 2^a is a view 60 in end elevation thereof.

Fig. 3 is a view in side elevation of one or more short pieces of wood dowel stock which may be advantageously employed in accordance with my invention. Fig. 3^a is a view in 65 end elevation of the same.

Fig. 4 is a view in side elevation of the piece of tubing shown in Fig. 2 after a piece of the dowel stock shown in Fig. 3 has been inserted thereinto to reinforce the same.

70 Fig. 5 is a view in side elevation of the reinforced tube shown in Fig. 4 after the same has been bent to desired shape or form. Fig. 5^a is a view in end elevation thereof.

Fig. 6 is a perspective view of the frame 75 of an article of furniture, such as a chair made in accordance with my invention.

Fig. 7 is a perspective view of a reed chair made in accordance with my invention with the usual seat omitted therefrom to more 80 fully disclose the structure thereof.

The invention is herein illustrated and will be herein described in connection with a reed or reed fabric chair because such a chair well represents an article of furniture of 85 common use and one which may be taken as an exemplification of the problems overcome by my invention.

In Fig. 6 is illustrated the bare frame of a substantially high back and side chair adopted to be covered with a suitable woven reed or reed fabric. Such a chair frame comprises a seat frame member 1 including side rails 2-2, a front rail 3 and a rounded rear rail 4 which may be made as an integral part of the side rails. 5 indicates the front pair of legs of the chair frame and 6 indicates the rear pair of legs of said frame.

90 The front legs 5 are of such height as to 95 extend a suitable distance above the seat 100

frame member 1. The bottom portions of said legs are substantially perpendicular while the top portions of said legs are bent laterally outward as shown. Said legs are 5 engaged with and secured to the seat frame in the plane of the front rail 3 in any suitable manner.

The rear pair of legs 6 are longer than the legs of the front pair and are bent at a 10 point between their ends where they are secured in any suitable manner to the rear part of the seat frame. In this instance the bottom parts of said legs extend downwardly from the seat frame and the top 15 parts of said legs extend upwardly and outwardly from said seat frame. The bottom portion of all of said legs are connected together by diagonal braces 7 and portions of all of said legs below the seat frame are 20 further braced therefrom by brace members 8.

The top ends or extensions of all of said legs are connected together by a U shaped top rail or bar 9 preferably of bent wood, 25 dowel stock.

Those portions of the legs above the seat frame member 1 receive a woven reed or reed fabric 10 which fabric is disposed upon the inside of said legs in the manner well 30 known, and the front rail is covered with a strip 11 of such fabric as best shown in Fig. 7.

From the above it is apparent that certain portions of the legs are exposed to view 35 in a finished chair and if such legs which were heretofore made of wood dowel stock were left smooth, they would not harmonize with the covering. The practice has been to make said legs in a manner to simulate a 40 reed or rattan wrapping thereon and this was done by circumferentially beading the same by rolling grooves thereinto. Such legs being made of wood are apt to split and crack after the chair has been finished, with 45 the result that the chair is rendered useless or has to be sold as a "second" with a resulting loss.

To overcome the difficulties and objections to this type of leg I have provided a frame 50 member in the form of a leg which comprises a thin metallic tube interiorly braced or reinforced either for its entire length or at certain points or places in the length thereof. Such a leg is best shown in Figs. 5 and 5a.

To form such a leg, I provide a piece of 55 thin walled sheet metal tubing 12 as shown in Fig. 1, of the desired length and the same may be either seamless or welded tubing. I then operate upon said tubing and circumferentially bead the same by rolling or otherwise 60 forming a groove or grooves 13 therein to produce the beading 14 thereon, best shown in Fig. 2. This beading is preferably helical to more closely simulate a wrapped appearance. Should such tubing

require trimming as to length, this may be done either before or after beading as mentioned.

To reinforce such a piece of tubing, I provide a piece of wooden dowel stock 15 of a 70 diameter snugly fitting the interior of the tubing and treat the same to a fluid to make it pliable or flexible enough for bending. Preferably soaking such stock in hot water 75 will make the same bendable. Said dowel stock 15, after being thus soaked in then inserted into one end of the tubing and forced into the desired position thereinto under endwise pressure and once in place therein can only be removed with much difficulty. 80 In this respect it is pointed out that the dowel stock may be of any desirable length; that is, it may be of a length approximating that of a the tubing or it may be in shorter 85 lengths or pieces which are disposed at different distance apart within said tubing. Thereby such dowel stock as is now considered as factory waste may be advantageously employed with an economic saving.

After the soaked dowel stock has been 90 placed within the tubing to reinforce the same, such reinforced tubing may be readily bent as shown in Fig. 5 to the desired shape, the dowel stock acting to prevent kinking or buckling of the tubing at the bend. Thereafter such portions as project beyond the 95 ends of the tubing are trimmed off and the reinforced tubing is then ready for use in a furniture article frame.

When a chair frame such as that shown in 100 Fig. 6 is to be made up, pieces of tubing reinforced as described, are bent into proper shape to form the legs 5 and 6. These legs are then secured to the seat frame 1 as by nailing the same thereto, it being pointed out that the tubing wall is not so thick or 105 heavy as to offer any substantial resistance to the driving of nails thereinto in the same manner as they may be driven into wood.

The bottom ends of the legs are then 110 braced together and to the seat frame and the U shaped top rail 9 is then secured to the top ends of the legs so that the framing as a whole is ready to receive its covering 10 115 of reed fabric or the like.

Such a reinforced tubing has many advantages as material for use in providing the framing of articles of furniture. It does not split, crack or splinter either before or after bending and it readily takes such 120 finishing paints or enamels as it is desired to apply thereto. It does not splinter in the manner of wood and where such tubing is reinforced at spaced points only, the weight of the chair is materially reduced. 125 Again making up the tubing in the manner described forms an economic outlet for the short pieces of dowel stock heretofore recognized as a factory waste, and the reinforced tubing is ready for use after bending with 130

out the necessity of drying the same by the application of heat. As is apparent such reinforced tubing is not only advantageous for use as legs in the furniture industry, but may be also employed as other parts of the framing where its peculiar characteristics makes it of advantage to do so.

5 While in describing my invention I have referred in detail to the form, arrangement and construction of the various parts thereof, as well as to the steps and the sequence thereof in producing the framing, the same is to be considered merely as illustrative so that I do not wish to be limited thereto except as may be pointed out in the appended claim.

I claim as my invention:

10 The method of making a furniture frame member or the like which consists in providing a thin walled metal tube, inserting a plurality of wooden dowel members therein in endwise spaced relation at least in part and then bending the composite structure at a zone containing such a dowel member.

15 25 In testimony whereof, I have hereunto set my hand, this 11th day of June, 1929.

LEWIS LARSEN.
